IN SITU COMBUSTION PRODUCTION METHOD

This invention relates to an in situ combustion method for producing hydrocarbons from a subterranean formation. In another aspect, this invention relates to a method for supplying oxidant to a combustion zone of a counterflow in situ combustion operation for producing hydrocarbons from a subterranean formation and preventing spontaneous combustion of the in place hydrocarbons at undesirable locations. The counterflow in situ combustion process referred to herein is sometimes referred to as the "inverse," "countercurrent," or "reverse" combustion process.

In situ combustion is commonly used to facilitate production of viscous hydrocarbons which are not readily produced by conventional production procedures. Typically, an in situ combustion arrangement may include an input or injection well for the introduction of oxygen-containing combustion-supporting fluid, such as air, and an output well for the removal of the desired hydrocarbons. Each of these wells extend from the surface of the earth into the formation desired to be produced. In the more conventional forward or direct in situ combustion process, a combustion front is initiated in the formation desired to be produced around the input well and combustion-supporting fluid is continually fed into the formation and to this front through said input well. The combustion front provides a radially expanding source of heat and functions to distill and reduce the viscosity of hydrocarbons in the formation. In the latter state, the hydrocarbons are capable of more freely moving through the formation to the input well where they may be recovered by conventional production means. In addition to creating the expanding source of heat, the combustion-supporting fluid is converted to hot combustion products that move away from the input well toward the output well while transporting reservoir hydrocarbons.

When used in formations containing very viscous hydrocarbons, the forward or direct combustion process often proves unsuccessful because of the buildup of a relatively immobile bank of viscous liquid hydrocarbons in the formation beyond the combustion front. This bank functions to seal the formation around the combustion front and thus impedes, or restricts completely, the flow of combustion-supporting fluid from the input well and through the formation. As a result, the combustion front dies and the recovery process becomes completely ineffective. In order to avoid the viscous hydrocarbon buildup problem encountered in the forward combustion process, the aforementioned counterflow combustion process has been developed. The counterflow combustion process is similar to the forward combustion process in that it utilizes input and output wells extending from the surface of the earth into the formation desired to be produced and also utilizes a combustion front in the formation to decrease the viscosity of hydrocarbons therein. The counterflow combustion process differs from the forward combustion process primarily in that the combustion zone is initiated into the formation around the output well rather than the input well.

Typically, in application of the counterflow combustion process, combustion is initiated around the output well by heating the formation and injecting an oxidant, such as air, into the heated area. Initially, the oxidant may be injected through either the input or output well. After combustion is initiated, however, the injection through the output well is terminated and the oxidant is introduced into the formation through only the input well. When the process is in operation the combustion zone moves radially outward from the output well while being supplied with oxidant, and possibly fuel, from the input well. From the latter relationship, the process derives the name of counterflow, inverse, reverse, or countercurrent combustion, since the combustion front moves in a reverse direction to that in the forward combustion process and in a direction countercurrent to the direction in which the oxidant moves. It is noted that in aforescribed forward combustion process the combustion front and the oxidant move in the same direction.

The oxidant introduced through the input well in the countercurrent combustion process functions to drive hydrocar-

bons toward the output well, as well as to maintain the combustion zone. Concurrently with the introduction of oxidant through the input well, hydrocarbons are removed from the output well. Hydrocarbons removed from the output well will have a low viscosity, since the heat generated by the combustion zone functions the lower the viscosity of hydrocarbons within the formation. However, contrary to the situation in the forward combustion process, the flow of gas and hydrocarbons is not impeded by the formation of a heavy blank of viscous hydrocarbons near the combustion front, since hydrocarbons upstream from the combustion front remain relatively cool and those downstream from the front are maintained at a low viscosity by the preheated formations around the output well.

The application of the countercurrent combustion process, however, presents a spontaneous ignition problem that is not encountered in a forward combustion process. Specifically, in the countercurrent combustion process it has been discovered that spontaneous ignition will take place in portions of the formation upstream from the advancing combustion front. Spontaneous ignition results from the slow oxidation of organic matter (in this case the crude within the formation being produced) by the oxidant as it flows through the formation from the injection well to the combustion front. This slow oxidation generates heat that increases the temperature of the formation. As the temperature increases, the rate at which the oxidation occurs increased until the temperature is sufficiently high that all, or nearly all, of the oxygen in the oxidant is consumed before it reaches the combustion front. When this occurs, there is little or no oxygen available to support the desired countercurrent combustion front, and as a result this front dies out. At or near this time, the portions of the formation remote from the output well and generally near the injection well, reach a temperature sufficient to support spontaneous ignition and thus a new and undesired combustion front is created. Typically, this front will form around the injection well and create, in effect, a direct combustion process.

The time required for spontaneous ignition within the formation is affected by such things as the character of the crude, the oxygen content of the oxidant, the rate of oxidant injection, and the reservoir temperature and pressure. The most controlling factor, however, is the ambient temperature of the reservoir. For nearly all reservoirs, but the most shallow (i.e., less than 500 feet from the surface), the ambient reservoir temperature will be sufficiently high (i.e., 85° F. or above) to promote spontaneous ignition near the injection well within a relatively short time, for example, in the order of 3 months.

Therefore, since countercurrent combustion operations are usually planned to last for periods ranging in years, it can be seen that spontaneous combustion in areas of the formation remote from the desired countercurrent combustion zone is likely to occur. With this occurrence, the combustion zone around the output well will die out and a new combustion zone will form around and spread radially from the input well, thus creating a direct combustion process. This direct combustion process will, in turn, be accompanied by the aforesaid problems encountered in conventional direct combustion processes. Thus, in countercurrent combustion processes, it has been found to be highly desirable to control the rate of oxidation in the formations upstream from the combustion zone to prevent spontaneous ignition within those portions of the producing formations.

It is therefore an object of this invention to provide an improved countercurrent in situ combustion production method. Another object of this invention is to provide a countercurrent in situ combustion process that will not permit spontaneous ignition of the in place hydrocarbons at undesirable locations. Yet another object of this invention is to provide an in situ combustion process that requires less equipment, labor, and power. Other aspects, objects, and advantages of the present invention will become apparent from a study of the disclosure, the appended claims, and the drawing.

The drawing shows the formation, wells, and a portion of the equipment utilized in the countercurrent in situ combustion production method of this invention.

In the drawing, at least one injection well 2 and one production well 4 extend from the surface of the earth downwardly through a subterranean hydrocarbon-containing formation 6. The injection well 2 and production well 4 are laterally spaced one from the other. The injection well 2 preferably has casing set through the production zone 6 with said casing affixed to said formation 6 to form a fluidtight seal. The casing of the injection well 2 is thereafter opened into the adjacent formation 6 at a position preferably an equal distance from the top and bottom 8, 10 of the hydrocarbon-containing formation 6 in order to assure substantially equal oxidant flow in both an upward and downward direction at the combustion zone (to be later described). A fracture 11 is formed by hydraulically fracturing methods known in the art from the opening in the injection well 2 through the hydrocarbon-containing formation 6 to a location adjacent a remote production well 4.

In order to provide additional protection against spontaneous combustion in the vicinity of the injection well 2, it is preferred that a gelled fluid bank 12 be formed within the formation 6 surrounding the injection well 2 over the entire thickness of the formation. The gelled fluid bank 12 can be formed by slowly injecting a volume of gelled fluid into the well 2 prior to forming the fracture 11. The gelled fluid bank 12 can be maintained during in situ combustion operations by periodically injecting slugs of gelled fluid into the formation 6. Gelled fluids that can be used with the method of this invention are, for example: solutions containing guar gum, polysaccharides, sodium silicate, and the like that raise the viscosity of the fluid to above 100 cp. Antioxidants can also be incorporated with the gelled fluid to protect against spontaneous combustion.

The surfaces of the fracture 11 extending through the fracture 6 are coated by injecting into the fracture 6 a fluid loss additive. The particles of the fluid loss additive adhere or are held by pressure against the surfaces of the fracture 11 and form a sealed coating 14 over preferably the entire surface of the fracture 6. The coating 14 prevents in place hydrocarbons from flowing into the fracture and oxidant that is to be passed through the fracture 6 from moving through the fracture surfaces and into the formation 6 at locations between the injection well 2 and the combustion zone 16 that is to be established. The fluid loss additive mixtures for use in coating the fractures in this invention can be, for example, mixtures of water, etc., with fluid loss additives such as cornstarch, wheat flour, gluten, carboxymethylcellulose, hydrolyzed polyacrylonitrile, and the like.

Examples of the fluid loss mixtures to be used are as follows:

FLUID LOSS MIXTURES

Liquid	Amount, bbl.	Fluid loss additive	Amount, lbs.
H ₂ O.....	1	Cornstarch.....	20
H ₂ O.....	1	Starch and Carboxymethylcellulose.....	20,2
H ₂ O.....	1	Guar gum.....	6

The volume of mixture used is dependent upon the total surface area of the fracture desired to be covered. A recommended volume would be, however, 500 to 2000 bbls.

A combustion zone 16 is thereafter formed across preferably the entire thickness of the production formation 6 contiguous to the production well. That combustion zone 16 is formed by igniting the in place hydrocarbons by various methods known in the art. An oxidant, preferably air, is then injected downwardly through the injection well, through the coated fracture, and to the combustion zone 16 for supplying oxygen to the combustion zone and moving said zone through

the hydrocarbon-containing formation 6. The pressure within the production well 4 is thereafter lowered and fluids entering the production well 4 are lifted to and recovered at the surface.

- 5 By providing a coating to the fracture surfaces for separating and maintaining the oxidant from substantial contact with the in place hydrocarbons during flow of the oxidant through the fracture 11 to the combustion zone, the occurrence of spontaneous combustion at undesirable locations within the formation 6 is greatly reduced. To further reduce the occurrence of spontaneous combustion it is preferred that the oxidant be cooled to a temperature at least below 90° F. prior to injecting said oxidant into the injection well. The oxidant can be cooled by cooling apparatus 18 such as a refrigeration system, cooling fins, heat exchangers, and other like methods known in the art. It is important, however, that the oxidant be cooled by the cooling apparatus 18 to at least 90° F. since heat is added to the oxidant by increasing the pressure on the oxidant sufficient to deliver said oxidant to the combustion zone 10 and by conduction of heat from the reservoir 6 to the oxidant as said oxidant passes through the fracture. So cooling the oxidant to below 90° F. assures that the oxidant passing through the fracture is at a temperature lower than the adjacent formation 6 and thereby continually cools and assists in preventing spontaneous combustion at undesirable locations.
- 15 By preventing mixing of oxidant and in place hydrocarbons and cooling the formation by the method of this invention, countercurrent in situ combustion can be conducted without the danger of spontaneous combustion at undesirable locations.
- 20 Other modifications and alterations of this invention will become apparent to those skilled in the art from the foregoing discussion and accompanying drawing and it should be understood that this invention is not to be limited thereto.

35 I claim:

1. A method of recovering hydrocarbons from a subterranean hydrocarbon-containing formation penetrated by at least one injection well and one production well spaced from said injection well, comprising:
40 forming a fracture through the hydrocarbon-containing formation from an injection well to a location adjacent a remote production well;
coating the surfaces of the fracture with sealing material;
establishing a combustion zone in a portion of the hydrocarbon-containing formation contiguous to the production well;
45 injecting an oxidant downwardly through the injection well, through the coated fracture and to the combustion zone for supplying oxygen to the combustion zone and moving said zone through the hydrocarbon-containing formation;
and
lowering the pressure within the production well and producing fluids entering said production well.
2. A method, as set forth in claim 1, including cooling the oxidant to a temperature at least below 90° F. prior to injecting said oxidant into the injection well.
- 55 3. A method, as set forth in claim 1, wherein the surfaces of the fracture are coated by injecting a mixture of water and fluid loss additive downwardly through the injection well and outwardly through the fracture.
4. A method, as set forth in claim 1, including injecting a volume of gelled fluid into the formation adjacent the injection well prior to fracturing the injection well and maintaining the bank of gelled gel fluid around portions of the injection well in the hydrocarbon-containing formation by periodically injecting slugs of gelled fluid into said formation.
- 60 5. A method, as set forth in claim 1, wherein the oxidant is air.
